UNITED STATES PATENT OFFICE.

BYERS GILLESPIE ROSS AND OLIVER BRINDLEY, OF PITTSBURGH, PENNSYLVANIA.

ATTACHMENT FOR MOVING-PICTURE MACHINES.

1,383,428.

Specification of Letters Patent.

Patented July 5, 1921.

Application filed September 18, 1919, Serial No. 324,537. Renewed March 18, 1921. Serial No. 453,480.

To all whom it may concern:

Be it known that we, BYERS GILLESPIE Ross and OLIVER BRINDLEY, citizens of the United States, residing at Pittsburgh, in the county of Allegheny and State of Pennsylvania, have invented a new and useful Improvement in Attachments for Moving-Picture Machines, of which improvement the following is a specification.

10 Our invention relates to improvements in attachments for moving picture machines and particularly to means for closing the shutter of one machine substantially simultaneously with the opening of the shutter of

15 the other machine.

The object of the invention is to employ a pair of moving picture machines, each of which is provided with the usual safety shutter and to utilize means in their operation by which one of said machines is thrown into operative relation with the screen; substantially simultaneously the other machine is thrown out of operative relation with said screen, whereby a series of pictures, comprising a number of reels, can be thrown upon the screen without the slightest apparent intermission.

We accomplish this by means of the device hereinafter more particularly described, reference being had to the accompanying drawings forming part hereof, in which—

Figure 1—is a rear elevation of the upper portion of a moving picture machine, with our improvement applied.

Fig. 2—is a side elevation of the same.

Fig. 3—is a plan view.

Fig. 4—is a front elevation.

Fig. 5—is a side elevation of one of the machines upon its ordinary base or support.

40 Fig. 6—is a rear, diagrammatic view of two machines with our improvement applied.

Fig. 7—is a plan view of the same.

Referring to the said drawings, 1 is a foundation or frame which may be of any suitable construction, upon which the aligned picture machines 2, 3, are supported; 4 is the wall of the compartment in which said machines are located, upon which is secured 50 in any suitable manner plug 5 for the support of electrical conductors 6, 7. 8 is a plate having a downward projecting flange *a*, provided with orifices *b*, for the reception of bolts or other suitable means of attaching 55 the same to the frame of the machines, 2, 3, respectively. In the upper side of each of

said plates an opening *c* is formed which is controlled by a shutter, 9. Upon the lower side of each of said plates a magnet, 10, of any usual construction is mounted. The 60 said magnets 10 are connected to the electrical conductors, 6, 7, respectively. An arm 11 is pivotally mounted upon each of said plates, closely adjacent to one end of each of said magnets, and the upper end of the arm 65 is adapted to engage when actuated by said magnets, the lower end of the arm 12, the said arm 12 being pivotally secured upon said plate immediately above the arm 11. The upper end of said arm 12 is adapted to 70 engage when actuated by said arm 11 the downwardly projecting member *d* of the crank whereby the horizontally disposed member *e*, of said crank, engages against a pin, *f*, secured in the forward end of the 75 shutter, whereby the said shutter is elevated when said arms and crank are actuated by the magnets.

Upon the side of said plates opposite that upon which said magnets are supported, the 80 actuating mechanism is supported or secured. The said mechanism comprises the operating lever 13, the free end of which rests upon the bracket 14, which is secured to and projects from each of said plates, the 85 opposite end of said lever being connected to the vertically disposed lever 15, the upper end of which terminates in a hooked or bifurcated portion which straddles the cylindrical portion of a member comprising 90 the collar, 17, and the gear wheel, 18, which is slidably mounted on the power shaft, 16, of the machine by means of a spline between said collar, 17, and the said gear wheel, 18, whereby when the said lever, 13, is thrown 95 into the position shown in solid lines, Fig. 3, the vertically disposed lever, 15, is shifted in an opposite direction and carries the gear wheel, 18, into mesh with the gear wheel, 21, which is mounted on the stud, 22, and on the 100 said plate, 8, thereby transmitting power from the shaft, 16, to said gear wheel, 21, the said power shaft, 16, being supported in bearings formed in the collars, 20 and 19. The said gear wheel, 21, has attached to one 105 side thereof a small gear wheel 23, which is mounted on said stud 22, and meshes with and transmits power to the gear wheel 24 mounted on the stud, 25, secured in said plate 8. The said gear 24 has secured thereto the member 26, which is preferably integral with said member and constitutes a

double cam, *i.e.*; its periphery constitutes a cam and upon one side a cam projection, 27, is secured, the function of which is to automatically throw gear wheel, 18, out of mesh with gear wheel, 21, at the conclusion of the run of a reel or film. In its rotation, the periphery cam actuates the arm, 28, one end of which rests upon the periphery of said member 26, the opposite end being attached to the vertically disposed rod 29, 29, the lower end of which in machine 2 is connected to the arm 30, mounted on shaft 31, and in machine 3 the lower end of said rod 29 is connected to the similar arm, 32, mounted on similar shaft, 33. The said shafts 31 and 33 are each provided with a finger, 34, 35, respectively, mounted on the extreme inner end thereof, which is adapted to alternately engage against the dual push button, 36, when said shafts are partially rotated. The said push button controls an electric current carried by said conductors, 6, 7, and is operated, as specified, for the purpose of conveying electric current alternately to, and cutting the same out from, the magnets for the purpose of alternately energizing and de-energizing the same, whereby the shutter which controls the openings, C, C, are alternately elevated and permitted to close when a reel has been finished on either of the machines. This operation is performed in such manner that with the closing of one of said openings the shutter of the other machine is simultaneously opened, the shutter falling by gravity when the magnet controlling the same is de-energized. This operation is done substantially instantaneous so that there is no perceptible intermission between the closing of one shutter and the opening of the other. The said shafts 31 and 33 are also provided with foot lever, 37, 38, by the operation of which the said shafts are rotated and the push button operated alternately by said finger 34, 35, and electric current is transmitted to, and cut out from, either of the magnets at will.

The operation of the device is as follows: One of the machines, which, for the purpose of illustration, we will call No. 1, which is 50 the machine shown to the left hand of Fig. 6, being in operation with its magnet de-energized, the operator will proceed to thread or charge machine No. 2 in the usual manner to start and when said machine No. 55 2 is ready with its magnet energized, move operating lever, 13, to the position shown in solid lines, Fig. 3, when the film in machine No. 1 is almost exhausted, that is to say,

when there remains about two feet of the film still unfed. The operation of throwing the horizontal lever into the position shown in solid lines causes the sliding gear to engage and transmit power to the double cam, which on one-half revolution throws the switch, cutting current out from the magnet of machine No. 2, causing the shutter thereof to drop and at the same time energizing the magnet of machine No. 1, operating the shutter to closed position, thereby throwing machine No. 1 out of operation and machine No. 2 into operation, with relation to the screen. The completion of the other half revolution of the cam wheel brings the projecting cam, 27, into contact with the operating lever of machine No. 2, throwing the sliding gear out of mesh, causing the gearing to remain idle with relation to the machine until this operation is repeated, which may be done as often as required. It is understood that upon the completion of the film in machine No. 2, machine No. 1 is operated in the same manner and the operation, as before stated, repeated as long as required.

One of the principal advantages of our invention is that one operator is dispensed with and better results obtained than when two operators are independently operating independent machines.

Having described our invention, what we desire to secure by Letters Patent, is:

1. The combination of a pair of picture machines, each of which is provided with a magnetically controlled aperture shutter, a magnet mounted on each of said machines, means to alternately simultaneously energize one of said magnets and de-energize the other and means operated by said magnets to control said shutters.

2. The combination of a pair of picture machines each of which is provided with an aperture shutter and a magnet, means operable by said magnet for closing one of the apertures simultaneously with the opening of the other aperture shutter and manually controlled means for actuating the means for automatically energizing either one of said magnets and simultaneously de-energizing the remaining magnet.

In testimony whereof, we have hereunto signed our names in the presence of two subscribing witnesses.
